UNITED STATES PATENT OFFICE

165,647

GLARE SHIELD

Harry F. George, Chicago, Ill.

Application December 15, 1949, Serial No. 6,639

Term of patent 14 years

(Cl. D14—6)

To all whom it may concern:

Be it known that I, Harry F. George, a citizen of the United States, residing at Chicago, in the county of Cook and State of Illinois, have invented a new, original, and ornamental Design for a Glare Shield, of which the following is a specification, reference being had to the accompanying drawing, forming a part thereof, in which:

Fig. 1 is a front elevation of a glare shield, showing my new design.

Fig. 2 is a top plan view.

Fig. 3 is an end elevation looking toward the lefthand end of Fig. 1.

Fig. 4 is an enlarged section on the line 4—4 of Fig. 1.

Fig. 5 is an enlarged section on the line 5—5 of Fig. 1.

I claim:

The ornamental design for a glare shield, as shown.

HARRY F. GEORGE.
